(57) **CLAIM**

The ornamental design of an impact handle for hand held surgical instruments, as shown and described.

DESCRIPTION

FIG. 1 is a perspective view of an impact handle for hand held surgical instruments showing my new design.

FIG. 2 is a front elevation view thereof.

FIG. 3 is a back elevation view thereof.

FIG. 4 is a right side elevation view thereof, the left side elevation view being a mirror image thereto.

FIG. 5 is a bottom plan view thereof; and,

FIG. 6 is a top plan view thereof.
